UNITED STATES PATENT OFFICE.

WILLIAM S. EATON, OF SAG HARBOR, NEW YORK.

ETCHING-MACHINE.

1,341,739.

Specification of Letters Patent.

Patented June 1, 1920.

Application filed January 24, 1919, Serial No. 272,842. Renewed April 23, 1920. Serial No. 376,172.

To all whom it may concern:

Be it known that I, WILLIAM S. EATON, a citizen of the United States, residing at Sag Harbor, in the county of Suffolk and State of New York, have invented certain new and useful Improvements in Etching-Machines, of which the following is a specification, reference being had therein to the accompanying drawings, which form a part thereof.

My invention relates to etching machines, and more particularly to pantographic etching machines adapted for use in preparing printing surfaces for acid etching.

In machines of the character to which my invention relates, the design to be etched is mechanically reproduced by a pantograph mechanism from suitable patterns, this mechanism being capable of various adjustments to control the scale of the reproduction, to extend or condense the reproduction as compared with the pattern, or to pitch the reproduction forwardly or backwardly. The changes in the design resulting from such adjustments, in no wise alter the quantity of movement of the tracing stylus, and thus permit variation in the reproduced design while using the same pattern.

A machine made in accordance with my invention is not designed to remove any portion of the printing surface, but merely to act upon the wax, or other resist, upon said surface, in a manner to expose portions of the surface to permit the acid to act thereon.

In using a machine made in accordance with my invention, it is essential to frequently remove the work tool or point from the printing surface, particularly when portions of the design being produced, are disconnected from other portions thereof, and to permit inspection of the work being done. The nature of this work requires little or no pressure from the work tool or point upon the printing surface, gravity being relied upon to secure the desired penetration of the wax, or other resist, by said tool or point.

I have discovered that while a machine is in use, there is no tendency of the work tool or point to scratch the printing surface beneath the wax, or other resist, but that there is a tendency of said work tool or point to mar this surface when the work tool or point is first brought into engagement therewith, resulting in the formation of small

dots upon said surface. As a consequence, the depth of the etched portion of the design is greater where these dots are formed, and many minute, darker spots occur in the imprints made from such surfaces. This condition is particularly true when the machine is used to do work upon lithographic stones, the material of which is so soft as to not offer sufficient resistance to the work tool or point to avoid this marring of the surface. For this reason it has been practically impossible heretofore to use machines of the type to which my invention relates, in the reproduction of a design upon lithographic stones.

Machines of the type used in removing a portion of the metal of the printing surface by means of a graver or a routing tool, wherein the tool is advanced toward the work, or set in relation thereto by means of a micrometer screw mechanism, cannot be used in removing the wax, or other resist, from printing surfaces to be acid etched.

With these conditions in mind, I have produced a machine wherein the work tool or point will descend by gravity toward the printing surface, this descent being controlled by an automatically acting resistance device, in a manner to permit the tool or point to penetrate the wax, or other resist, and yet gather so little momentum as to cause it to come into contact with the printing surface, with an impact sufficiently light to avoid, or with the absence of such a forceful impact to cause, even the most minute penetration of this surface thereby. This device is so constructed as to permit it to be adjusted with great nicety and precision, while permitting the rapid removal of the tool from the printing surface.

While the field of greatest utility of a machine made in accordance with my invention, is its use in preparing lithographic stones, I so construct it that it may be readily so set as to be adapted for use upon metal plates.

The invention consists primarily in a machine of the character described, embodying therein a support for a work tool or point, a tool carried thereby, a work bed, means adapted to impart relative universal movement upon a single plane, to said support and said work bed, a member operative upon said support to move it away from said work bed, means whereby said

member may be moved away from said support, to permit said support to descend by gravity toward said work bed and bring said work tool or point into operative engagement with the printing surface, and a resistance device operative upon said support controlling the descent thereof under gravity, whereby sufficiently forceful impact of said work tool or point with the printing surface, to mar same, is prevented; and in such other novel features of construction and combination of parts as are hereinafter set forth and described, and more particularly pointed out in the claims hereto appended.

Referring to the drawings,

Figure 1 is a front elevation of the upper portion of a machine embodying my invention;

Fig. 2 is a plan view thereof, upon a larger scale, with a portion of the work tool or point support broken away;

Fig. 3 is a vertical section of the head of the machine; and

Fig. 4 is a detailed view of a portion of the resistance mechanism.

Like numerals refer to like parts throughout the several views.

In the embodiment of my invention shown in the drawings, 1 indicates the main frame of the machine, upon the table 2 of which is mounted a suitable holder 3 for the pattern. Supported by the table 2 is a column 4 having a head 5 provided with suitable ball cups 6, 7 and 8. Carried by the head 5 is a block 9 to which is permanently secured a shelf 10 upon which the work bed 11 is adjustably mounted so as to have movement either laterally of the machine, or longitudinally thereof. This adjustability of the work bed 11 is secured by means of a carriage 12 mounted in longitudinally extending tracks 13 upon the shelf 10, the work bed proper 11 being slidably mounted by means of the dove tail slide connection 14, between it and said carriage 12, to have movement laterally of the machine upon said carriage. For imparting movement of the carriage 12 and the work bed 11 mounted thereon longitudinally of the machine, I employ a rack 15 carried by the shelf 10, with which the gear 16 upon the shaft 17, meshes, said shaft being mounted in suitable bearings upon the carriage 12. Also mounted in the carriage 12 is a shaft 18 carrying a pinion 19 meshing with a rack 20 upon the underside of said work bed, thus permitting the movement of said work bed laterally of the machine upon the carriage 12.

Along the front edge of the work bed 11 is a plate 21 between which, and a movable dog 22, the material of the printing surface is adapted to be held. Said dog 22 is slidably mounted in a groove 23 upon said

work bed, being adjustably mounted upon the actuating rod 24, by means of coöperating screw threads thereon, and upon said rod. Said dog is brought into engagement with the material of the printing surface 26 by means of the spring 25 acting upon said rod.

In the accompanying drawings I have illustrated the printing surface upon which work is to be done, as consisting of a lithographic stone 26, although as will more fully appear hereinafter, the machine is capable of such adjustment as to be used upon other types of printing surfaces, such as copper plates, or aluminum or zinc plates used in the lithographic art. Throughout the specification I have referred to the material upon which work is to be done as a printing surface, or as material having a printing surface, it being understood that these terms are employed to distinguish the kind of work which the machine is particularly designed to do, from other kinds of work, such as engraving upon jewelry.

Positioned above, and projecting over, the work bed 11, is an arm 27, or other suitable support for the work tool or point 28, this arm, or other support, being adapted to have movement toward, or from, the work bed 11, to bring the work tool or point into engagement with the printing surface 26, or out of engagement therewith.

In order to reproduce the design upon the printing surface, it is necessary that the work bed 11 and the arm, or other support, 27, for the work tool or point 28, have relative universal movement upon a single plane, this result being secured in the form of the invention shown, by imparting such movement to the arm, or other support, 27, while maintaining the work bed 11 stationary. This construction is particularly adaptable for work upon lithographic stones, because of the liability of the moving inertia of parts to develop imperfections in a reproduction when a heavy weight has to be moved by the actuating means for the movable member.

In the embodiment of the invention shown in the drawings, the arm 27 is carried by a carriage 29 having inverted ball cups 30, 31 and 32 oppositely disposed to the ball cups 6, 7 and 8 respectively, and supported therefrom by means of the bearing balls 33, 34 and 35. The diameter of each of said balls is considerably smaller than that of the coöperating bearing cups, to permit the desired range of movement of said carriage.

Carried by the carriage 29 is a yoke 36 in which is pivotally mounted a frame 37, the axis of the pivots of said frame being parallel with the printing surface 26. Said frame has a forwardly extending arm 38, the end of which is shaped to conform to 130

the upper portion of the arm 27, said arm 38, intermediate the end thereof and the yoke 36, being provided with a ring 39 through which the arm 27 passes, said ring being acted upon by a screw 40 carried by the arm 38 in a manner to draw the arm 27 into engagement with the end of the arm 38, and thus hold it firmly in position with relation to said frame, while permitting 10 said arm 27 to be loosened in its mounting in a manner to permit it to be adjusted axially thereof, to vary the position of the work tool or point 28 in relation to the printing surface. The frame 37 is so 15 formed adjacent the point of its pivotal support, as to engage the arm 27, thus causing the actuation of the screw 40, to move said arm toward, or from, two bearing surfaces upon said frame, and upon the arm 20 38, between which surfaces the ring 39 is located.

Since the arm, or other support, 27, projects radially of the axis of support of the frame 37, there is a normal tendency of said 25 arm 27 to drop by gravity, so as to bring the work tool or point 28 into engagement with the printing surface 26. To place the movements of the arm 27 under the control of the operator, I provide a supporting bar 30 41, upon which the arm 27 normally rests, and by which it is normally held out of engagement with the printing surface. This bar is of sufficient length to permit the desired range of movement of the arm 27. Said bar 41 is mounted in a suitable bearing 35 in the head 5, being normally thrust toward the arm 27 by means of the spring 42 seated between said head 5 and a collar 43, upon the stem 41^a supporting said bar, and also by 40 means of the actuating mechanism for said bar, which consists of a pull rod 44, a crank shaft 45, acted upon by a torsion spring 46, and a link 47 acting upon said crank shaft, and connected to a foot treadle, or any other 45 desired mechanism not shown, for actuating said bar.

The springs 42 and 46, as heretofore stated, have a normal tendency to thrust the bar 41 upwardly in a manner to move the 50 arm 27 and the work tool or point 28 carried thereby, away from the printing surface 26. When it is desired to bring said work tool or point into engagement with the printing surface, it is merely necessary 55 to draw the bar 41 downwardly against the tension of said springs, thus permitting the arm 27 to descend by gravity. The movement of the bar 41, however, is, in the actual use of the machine, very rapid, so that the 60 arm 27, even though its movement is not great acquires sufficient momentum to cause a sufficiently heavy impact of the work tool or point 28, with the printing surface, to result in its not only penetrating the wax, or 65 other resist, upon said surface, but by reason

of the fineness of the point of this tool to also penetrate said printing surface to a very slight extent, but sufficient to cause a subsequent acid etching of this surface, to erode the walls of this very light depression 70 or dot, in a manner to produce a marked, but slight, imperfection in the plate. Hence, while the marring of the plate is very slight, this error becomes exaggerated by the subsequent etching operation. If the material 75 of the printing surface be sufficiently hard to resist penetration of the work tool or point, likelihood of thus marring the plate is somewhat remote, but if the surface be soft, like in lithographic stones, or even in 80 zinc or aluminum lithographic plates, this marring will occur substantially every time the work tool or point is brought into engagement with the printing surface, although the likelihood of marring is very 85 much less with the metal surfaces than with the lithographic stones. In order to permit the use of the machine for reproducing designs upon lithographic stones, or other 90 printing surfaces apt to be marred as a result of the impact of the work tool or point 95 28 therewith, I provide a resistance or retard device operative upon the arm 27, or other support for the work tool, which will have the effect of controlling the rate of movement of said arm, or other support, in a manner to prevent the accumulation of force from the moving inertia of said arm, or other support, sufficient to cause the impact of the work tool or point with the 100 printing surface, to more than penetrate the wax, or other resist, thereon. In fact, the penetration of said wax, or other resist, will result from the dead load of the arm, or other support, and the work tool or point 105 carried thereby, instead of as a result of the force of the impact of the work tool or point therewith.

This resistance device comprises a cylinder 48 having slidably mounted therein a 110 cup-shaped plunger 49, carrying a rod 50, provided with an adjustable stop 51. Projecting from, and movable with, the frame 37, is a forked arm 52, straddling the rod 50, and adapted to engage beneath the stop 115 51. The cylinder 48 is partially filled with a suitable fluid such as oil, or, if desired, mercury could be used, the purpose of which is to seal the lower edge of the plunger 49, and retard the upward movement thereof. 120

Carried by the plunger 49 is a vent valve consisting of a casing 53, having a valve seat toward the bottom thereof, and a ball valve 54 mounted within said casing and upon said seat, said casing being provided 125 with a reduced neck 55 having a port there-through communicating with the interior of the plunger 49. Also carried by the plunger 49 is a regulating device consisting of a casing 56 having openings therein commu- 130

nicipating with atmosphere, and a screw actuated needle valve 57 controlling a port in the neck 58 in communication with the interior of said plunger 49. By this construction the rapid descent of the plunger 49 is permitted, as a result of the free venting action through the valve casing 53, and the capability of movement of the arm 52 away from the stop 51, while the upward movement thereof may be exactly controlled by the proper regulation of the volume of air admitted within the plunger 49, through the regulating device.

To permit adjustment of the machine so as to adapt it for work either upon lithographic stones, or upon thinner printing surfaces, I so support the yoke 36 and the bar 40 that they may be adjusted toward, or from, the carriage 29, so as to space the arm 27 closer, or more remote from the work bed 11, according to the thickness of the material of the printing surface upon which the work is to be done.

In the form of the invention shown, the stem 41^a supporting the rod 41, is made in two sections, one of which, as 59, is telescopically mounted in relation to the other, this section being set in its adjusted position by means of the set screw 60, or in any other desired manner. The yoke 36 is mounted in a distance block 61 by means of the set screw 62, said distance block being removably mounted in the carriage 29, so that by a removal of this block, the stem of the yoke 36 may be mounted directly upon the carriage by means of the screw 63. The stop 51 being adjustably mounted upon the rod 50, said stop may be adjusted to conform with other adjustments in the machine.

The carriage 29 may be actuated in conformity with the pattern, by any desired mechanism, insuring the universal movement of said carriage upon a single plane. This mechanism in the form of the invention shown, comprises a transmitter arm 64 having a tracing point or stylus 65 slidably mounted in the lower end thereof, so as to follow the pattern irrespective of the oscillations of said arm 64. This arm is mounted in a yoke 66 by means of shoes 67, embracing an angular portion of said arm 64, and pivotally mounted in a ring 68, which ring in turn is pivotally mounted by means of suitable pivot screws 69 in said yoke 66. The axes of the pivot screws 69 and of the pivots of the shoes 67, extend at right angles to each other. The yoke 66 is carried by a sleeve 70 adjustably mounted upon the column 4, the adjustment of this sleeve being secured by the rack and pinion mechanism 71.

The ring 68 is provided with diametrically opposite lugs 72, having bearings therein as indicated in dotted lines in Fig. 3, each of which bearings is adapted to be en-

gaged by the pivot screws 69 to permit the adjustment of the machine to either condense, or extend, the reproduction, or vary the width thereof with relation to other dimensions, the height remaining constant at 70 any scale of adjustment.

The upper end of the arm 64 is pivotally mounted in a ring 73, which ring in turn is pivotally mounted upon the carriage 29, the axes of the pivots connecting said ring with said carriage extending at right angles to the pivots connecting the transmitter arm with said ring.

To permit the adjustment of the machine for tilting the reproduction, or giving it a forward or a backward inclination, the yoke 66 is connected with the collar 70 by means of the pivot screw 74, the axis of which pivot extends at right angles to the axis of the column 4. To permit the setting of the collar 70 in any adjusted position, I split this collar as shown in Fig. 3, and provide a clamp screw 75 by means of which the collar may be clamped upon the column 4.

The operation of the herein described machine is substantially as follows:—

In pantographic engraving machines of the type where the work bed or plate receives universal movement, the right or left of the design, and the top and bottom of the pattern, bear the same relation in the reproduction. In other words, with this type of machine, the reproduction, except as to the scale, coincides with the pattern. In the type of machine, however, in which the work tool or point has movement in relation to the work bed, the latter being immovable, everything is reversed in the reproduction, the right becoming the left, the left the right, the bottom the top, and the top the bottom.

The operation of the two types of machines, however, is substantially identical, this variance in the character of the reproduction necessitating merely a proper provision therefor in the production of the pattern.

Where letters are to be reproduced, and the type of machine to which my invention relates is largely used for such reproductions, the machine employing a movable work bed, requires a pattern wherein the characters are like ordinary types and arranged in the same manner, the characters, however, being depressed instead of raised.

In a machine in which the work tool or point has movement, however, it is necessary to use a pattern such as is used in the other type of machine, set upside down, so as to bring the right of the pattern to the left of the machine, unless the work upon the printing surface is to appear upside down. In this type of machine, however, the letters in reverse will read from left to right to insure their proper positioning in 130

the reproduction. When these conditions are complied with, the letters of the reproduction will be properly placed upon the printing surface, but in the reverse, so as to insure a proper imprint therefrom.

The pattern is placed upon the holder 3 within the operative range of the stylus 65. In adjusting a machine to control the scale of reproduction, the screw 75 is released, 10 and the collar 70 moved by means of the rack and pinion mechanism 71, toward or from the tracing stylus 65, thus varying the fulcrum point afforded by the bearing shoes 67 and the pivot screws 69. If the movement be toward said stylus, the length of 15 the portion of the arm between said fulcrum point and said stylus will be diminished, and the length of the portion of said arm between said fulcrum point and the 20 carriage 29 will be increased, thus increasing the scale of reproduction, but if the movement be away from said stylus, this condition will be reversed, and the scale of the reproduction will be reduced. By dropping 25 the ring 68 with relation to the pivot screws 69, the fulcrum of the shoes 67 only, will be varied, thus increasing the leverage at which the arm 64 acts, as to the movements of the carriage laterally of the machine, the leverage at which it acts for imparting movement to the carriage longitudinally of the machine, remaining the same. This extends the letters. If, however, the 30 ring 68 be reversed and raised with relation to said pivot screws, the leverage at which the arm 64 acts upon the carriage laterally of the machine, will be reduced, while the effective leverage, longitudinally of the machine, will remain the same, so that the 35 letters will be condensed. This raising or lowering of the ring 68 is accomplished by means of the lugs 72.

If the yoke 66 be tilted to the left (Fig. 1) upon the pivot screw 74, the axes of the 40 pivots 69 will extend obliquely to the axis of the arm 64, so that a longitudinal oscillation of said arm will result in a slight movement of the carriage to the left at one side of the center of the pattern, and to the 45 right at the other side of said center, simultaneously with its longitudinal movement, thus tilting the reproduction slightly to the right. If the yoke 66 be tilted to the right, the movement of the carriage 29 will be opposite to that above described, and the 50 reproduction will be tilted to the left. The amount of tilting of the reproduction will be governed by the angle of obliquity of the axes of the pivots 69 in relation to the axis 55 of the arm 64, the greater the angle of obliquity, the greater the tilt of the reproduction. I have found it necessary, to secure a desirable effect when tilting letters, to release the screw 40 and adjust the support or

arm 27 so as to bring the work tool or point 65 28 closer to the frame 37.

As the tracing point or stylus 65 is moved over the pattern, corresponding movement, to an extent, however, determined by the adjustment of the machine, will be imparted 70 to the carriage 29, but in the reverse direction, the transmitter arm 64 acting as a lever, one arm of which carries the stylus and the other arm of which is connected by a universal joint with said carriage, this lever 75 being movable about a universal joint afforded by the ring 68, shoes 67, yoke 66, and pivot screws 69, intermediate the stylus and the carriage.

With the movement of the carriage 29, 80 the support or arm 27 is moved over the printing surface 26, so that when the work tool or point 28 is in the operative relation to said printing surface, portions of the wax, or other resist, conforming to the design to be etched, will be removed from said surface, so as to expose the metal through said wax, or other resist. The design of the pattern is thus reproduced upon said printing surface, but upon a different scale. 85

When it is desired to bring the work tool or point 28 into engagement with said printing surface 26, it is merely necessary to rock the shaft 45 against the tension of the spring 46, thus exerting a downward pull upon 90 the link 44 to draw the stem 41^a downwardly against the tension of the spring 42, and move the supporting bar 41 away from the arm 27. This movement of the bar 41 permits gravity to act upon the arm 27, and 95 were it not for the resistance or retard device, said arm would follow the bar 41 and come to rest only with the impact of the tool 28 with the printing surface. This impact, as stated above, would have the effect 100 of forming a dot upon this surface, and since, in the operation of the machine, it is not feasible to control the rate of movement of the arm 27 through the bar 41, said resistance or retard device is essential to avoid 110 this forceful impact and the resultant marring of said surface. With the rocking movement of the frame 37, with the descent of the arm 27, the weight of this arm will move the forked arm 52 upwardly, thus, 115 through the stop 51 and rod 50, raising the plunger or bell 49. The ball valve 54 normally closes the port 55, so that the upward movement of said plunger has a tendency 120 to develop a subatmospheric pressure in the upper portion thereof above the level of the fluid in the cylinder 48, and develop a resistance to the movement of this plunger, which would actually prevent the contact of the work tool or point 28 with the printing surface, were it not for the regulating device, 125 which will gradually admit air into said plunger in volume sufficient to tend to bring

the pressure therein to atmosphere, and thus permit a continuance of this movement. By regulating the volume of the air flowing through the port 58 by means of the needle valve 57, the rate of movement of the plunger may be so controlled as to permit the desired movement of the arm 27, but have this movement so gradual that the work tool or point will come to rest upon the printing surface after penetrating the wax, or other resist, without any such impact as will mar the plate. In fact the penetration of the wax, or other resist, will be by a gradual movement.

15 The extent of movement of the arm 27 is not great, so that while it is very gradual, there is no such relay as will interfere with the capacity of the machine. While the machine is at work, the atmospheric pressure within the plunger or bell 49, will avoid any tendency of the resistance or retard mechanism to raise the point from the work, the weight of the arm 27 holding this plunger 49 in the raised position.

20 25 When it is desired to raise the work tool or point from the printing surface, it is merely necessary to release the shaft 45, thus permitting the springs 46 and 42 to raise the supporting arm 27, the forked arm 30 35 40 45 50 55 60 65 70 75 80 85 90 95 100 105 110 115 120 125 130 moving away from the stop 51, so as to relieve the plunger from the load of said arm. Immediately that said plunger is relieved from this load, the dead weight thereof will cause the plunger to descend in the piston 48, the air within said plunger being vented through the port 55 and about the valve 54 with sufficient rapidity to permit the plunger to quickly descend so as to be in position preparatory to the next actuation of the bar 41 to bring the work tool or point into engagement with the printing surface.

The rack and pinion mechanism 15, 16 and 17 is used for positioning the printing surface so as to secure the proper line spacing of the reproduction, while the rack and pinion mechanism 18, 19 and 20 is used to impart a lateral movement to said surface, to secure the proper spacing of the letters in a line.

Of course the weight of the arm 27 between the frame 37 and the work tool or point 28 must be sufficient to overbalance the portion of the arm upon the other side 55 of the pivots of said frame, the arm 52 and the plunger or bell 49 and its appurtenances.

I believe it to be broadly new to provide a machine of this character wherein the movement of the support or arm for the work tool or point is so controlled as to avoid the marring of the printing surface, as a result of the impact of the work tool or point therewith, thus adapting the machine for use upon lithographic stones or other material, the printing surface of which may

be marred even with a slight impact of the work tool or point therewith.

It is not my intention to limit the invention to the details of construction shown in the accompanying drawings, it being apparent that such may be varied without departing from the spirit and scope of the invention.

Having described the invention what I claim as new, and desire to have protected by Letters Patent, is:—

1. A machine of the character described, embodying therein a movable support for a work tool or point, a work tool or point carried thereby, a work bed, means adapted to impart relative universal movement upon a single plane, to said support and said work bed, a member operative upon said support to move it away from said work bed, means whereby said member may be moved away from said support to permit said support to descend by gravity toward said work bed, and bring said work tool or point into operative engagement with a printing surface upon said work bed, and a resistance device operative upon said support to control the descent thereof under gravity, whereby sufficiently forceful impact of said work tool or point with the printing surface, to mar same, is prevented.

2. A machine of the character described, embodying therein a movable support for a work tool or point, a work tool or point carried thereby, a work bed, means adapted to impart relative universal movement upon a single plane, to said support and said work bed, a member operative upon said support to move it away from said work bed, means whereby said member may be moved away from said support to permit said support to descend by gravity toward said work bed, and bring said work tool or point into operative engagement with a printing surface upon said work bed, and a resistance device operative upon said support to control the descent thereof under gravity, whereby sufficiently forceful impact of said work tool or point with the printing surface, to mar same, is prevented, including therein a calibrating device whereby the rate of movement of said support may be regulated.

3. In a machine of the character described, embodying therein a work bed, a pivotal support for a work tool or point projecting over the work bed, the axis of the pivots of said support being parallel with the surface of said work bed, a work tool or point carried thereby, means adapted to impart relative universal movement upon a single plane to said support and said work bed, a member operative upon said support to move it away from said work bed, means whereby said member may be moved away from said support to permit said support to move under gravity and bring said work

- tool or point into operative engagement with a printing surface upon said work bed, a resistance device, a stop carried thereby, and an arm projecting radially of the axis of the 5 pivots of said support projecting beneath said stop, so as to operatively engage same, whereby said resistance device is operative upon said support to control the descent thereof under gravity and avoid a sufficiently force- 10 ful impact of said work tool or point with the printing surface, to mar same, and said support may be moved away from said work bed, independently of said resistance device.
4. A machine of the character described, 15 embodying therein a movable support for a work tool or point, a work tool or point carried thereby, a work bed, means adapted to impart relative universal movement upon a single plane, to said support and said work 20 bed, a member operative upon said support to move it away from said work bed, means whereby said member may be moved away from said support to permit said support to descend by gravity toward said work bed, a cylinder, a plunger slidably mounted therein, a vent valve whereby the pressures within said cylinder 25 may be relieved to permit the rapid movement of said plunger in one direction, a regulating device adapted to permit air to gradually enter said cylinder to regulate the rate of movement of said plunger in the opposite direction, and operative connections 30 between said plunger and said support for the work tool or point, whereby the descent of said support under gravity, is controlled, and sufficiently forceful impact of the work 35 tool or point with the printing surface, to mar same, is prevented.
5. A machine of the character described, 40 embodying therein a movable support for a work tool or point, a work tool or point carried thereby, a work bed, means adapted to impart relative universal movement upon a single plane, to said support and said work bed, a member operative upon said support to move it away from said work bed, means 45 whereby said member may be moved away from said support to permit said support to descend by gravity toward said work bed, and bring said work tool or point into operative engagement with a printing surface 50 upon said work bed, a cylinder, a plunger slidably mounted therein, a vent valve whereby the pressures within said cylinder may be relieved to permit the rapid movement of said plunger in one direction, a 55 regulating device open to atmosphere and having a port communicating with the interior of said cylinder, whereby air is permitted to enter said cylinder, and a valve controlling the capacity of said port, where- 60 by the volume of air passing through said 65 port is regulated, to control the rate of movement of said plunger in the opposite direction, and operative connections between said plunger and said support for the work tool or point, whereby the descent of said support under gravity, is controlled, and sufficiently forceful impact of the work tool or point with the printing surface, to mar same, is prevented. 70
6. A machine of the character described, 75 embodying therein a movable support for a work tool or point, a work tool or point carried thereby, a work bed, means adapted to impart relative universal movement upon a single plane, to said support and said work 80 bed, a member operative upon said support to move it away from said work bed, means whereby said member may be moved away from said support to permit said support to descend by gravity toward said work bed, and bring said work tool or point into operative engagement with a printing surface upon said work bed, a cylinder, a plunger slidably mounted therein, a vent valve whereby the pressures within said cylinder may be relieved to permit the rapid movement of said plunger in one direction, a regulating device adapted to permit air to gradually enter said cylinder to regulate the rate of movement of said plunger in the opposite direction, a rod carried by said plunger, a stop mounted upon said rod, and an arm carried by said support, 85 projecting beneath and adapted to engage said stop, whereby the descent of said support under gravity, is controlled, and sufficiently forceful impact of the work tool or point with the printing surface, to mar same, is prevented, and movement of said support in the opposite direction, independently of said plunger, is permitted. 90
7. A machine of the character described, 95 embodying therein a movable support for a work tool or point, a work tool or point carried thereby, a work bed, means adapted to impart relative universal movement upon a single plane, to said support and said work bed, a member operative upon said support to move it away from said work bed, means 100 whereby said member may be moved away from said support to permit said support to descend by gravity toward said work bed, and bring said work tool or point into operative engagement with a printing surface upon said work bed, a cylinder, a plunger slidably mounted therein, a casing carried by said plunger and communication therewith through a port, said casing having a seat about said port, a gravity valve mounted in said casing, cooperating with said seat, 105 whereby the pressure within said cylinder may be relieved to permit the rapid movement of said plunger in one direction, and said port is closed when movement is imparted to said plunger in the opposite direction, 110 115 120 125 130

a second casing carried by said plunger having a port communicating therewith, a needle valve carried by said casing, whereby the volume of air admitted to said plunger may be regulated to insure the desired slow rate of movement of said plunger in the opposite direction, and operative connections between said plunger and said support for the work tool or point, whereby the descent of said support under gravity, is controlled, and sufficiently forceful impact of the work tool or point with the printing surface, to mar same, is prevented.

8. A machine of the character described, embodying therein a movable support for a work tool or point, a work tool or point carried thereby, a work bed, means adapted to impart relative universal movement upon a single plane, to said support and said work bed, a member operative upon said support to move it away from said work bed, means whereby said member may be moved away from said support to permit said support to descend by gravity toward said work bed, and bring said work tool or point into operative engagement with a printing surface upon said work bed, a cylinder, a plunger slidably mounted therein, a casing carried by said plunger and communicating therewith through a port, said casing having a seat about said port, a gravity valve mounted in said casing, coöperating with said seat, whereby the pressure within said cylinder may be relieved to permit the rapid movement of said plunger in one direction, and said port is closed when movement is imparted to said plunger in the opposite direction, a second casing carried by said plunger having a port communicating therewith, a needle valve carried by said casing, whereby the volume of air admitted to said plunger may be regulated to insure the desired slow rate of movement of said plunger in the opposite direction, a rod carried by said plunger, a stop mounted upon said rod, and an arm carried by said support, projecting beneath and adapted to engage said stop, whereby the descent of said support under gravity, is controlled, and sufficiently forceful impact of the work tool or point with the printing surface, to mar same, is prevented, and movement of said support in the opposite direction, independently of said plunger, is permitted.

9. A machine of the character described, embodying therein a movable support for a work tool or point, a work tool or point carried thereby, a work bed, means adapted to impart relative universal movement upon a single plane, to said support and said work bed, a member operative upon said support to move it away from said work bed, means whereby said member may be moved away from said support to permit said support to descend by gravity toward

said work bed, and bring said work tool or point into operative engagement with a printing surface upon said work bed, a resistance device operative upon said support to control the descent thereof under gravity, whereby sufficiently forceful impact of said work tool or point with the printing surface, to mar same, is prevented, and independent means whereby said support for the work tool or point, and said resistance device, may be adjusted toward, or from, said work bed, to adapt the machine for use upon printing surfaces, the materials of which vary in thickness.

10. A machine of the character described, embodying therein a work bed, a carriage mounted to have universal movement upon a single plane, a yoke carried by said carriage, a frame pivotally mounted within said yoke, the axis of the pivots of said frame extending parallel with said work bed, an arm projecting over said work bed, means whereby said arm is adjustably mounted in said frame, a work tool or point carried by said arm, a transmitter arm, a universal joint connecting said arm with said carriage, a support for said arm intermediate the ends thereof, a universal joint connecting said transmitter arm with said support, a member operative upon said support to move it away from said work bed, means whereby said member may be moved away from said support to permit said support to descend by gravity toward said work bed, and bring said work tool or point into operative engagement with a printing surface upon said work bed, and a resistance device operative upon said support to control the descent thereof under gravity, whereby sufficiently forceful impact of said work tool or point with the printing surface, to mar same, is prevented.

11. A machine of the character described, embodying therein a shelf having tracks thereon, a carriage slidably mounted on said tracks, a work bed mounted upon said carriage by means of a slide connection extending at right angles to said tracks, coöperating means carried by said shelf and said carriage, whereby said carriage may be moved along said tracks, coöperating means upon said carriage and said work bed whereby said work bed may be moved upon said carriage at right angles to said tracks, a carriage mounted to have universal movement upon a single plane, a movable support for a work tool or point mounted upon said carriage, a work tool or point carried thereby, means adapted to actuate said universally movable carriage, a member operative upon said support to move it away from said work bed, means whereby said member may be moved away from said support to permit said support to descend by gravity toward said work bed, and bring

- said work tool or point into operative engagement with a printing surface upon said work bed, and a resistance device operative upon said support to control the descent thereof under gravity, whereby sufficiently forceful impact of said work tool or point with the printing surface, to mar same, is prevented.
12. A machine of the character described, embodying therein a work bed, a carriage mounted to have universal movement upon a single plane, a movable support for a work tool or point mounted upon said carriage, a work tool or point carried thereby, a transmitter arm, a universal joint connecting one end of said arm with said carriage, a support for said transmitter arm, a universal joint connecting said support with said transmitter arm intermediate the ends thereof, means whereby said support may be adjusted toward and from said carriage to vary the operative leverage of said arm, to vary the scale of reproduction, a member operative upon said movable support to move it away from said work bed, means whereby said member may be moved away from said support to permit said support to descend by gravity toward said work bed, and bring said work tool or point into operative engagement with a printing surface upon said work bed, and a resistance device operative upon said support to control the descent thereof under gravity, whereby sufficiently forceful impact of said work tool or point with the printing surface, to mar same, is prevented. 70
13. A machine of the character described, embodying therein a work bed, a carriage mounted to have universal movement upon a single plane, a movable support for a work tool or point mounted upon said carriage, a work tool or point carried thereby, a transmitter arm, a universal joint connecting one end of said arm with said carriage, a support for said transmitter arm, a universal joint connecting said support with said transmitter arm intermediate the ends thereof, means whereby said support may be adjusted toward and from said carriage to vary the operative leverage of said arm, to vary the scale of reproduction, means whereby said support may be tilted to one side or the other, to tilt the reproduction, means whereby said support for the work tool or point may be adjusted radially of its pivots, a member operative upon said support to move it away from said work bed, means whereby said member may be moved away from said support to permit said support to descend by gravity toward said work bed, and bring said work tool or point into operative engagement with a printing surface upon said work bed, and a resistance device operative upon said support to control the descent thereof under gravity, whereby sufficiently forceful impact of said work tool or point with the printing surface, to mar same, is prevented. 95
14. A machine of the character described, embodying therein a work bed, a carriage mounted to have universal movement upon a single plane, a pivotal support for a work tool or point mounted upon said carriage, a work tool or point carried thereby, a transmitter arm, a universal joint connecting one end of said arm with said carriage, a support for said transmitter arm, a universal joint connecting said support with said transmitter arm intermediate the ends thereof, means whereby said support may be adjusted toward and from said carriage to vary the operative leverage of said arm, to vary the scale of reproduction, means whereby said support may be tilted to one side or the other, to tilt the reproduction, means whereby said support for the work tool or point may be adjusted radially of its pivots, a member operative upon said support to move it away from said work bed, means whereby said member may be moved away from said support to permit said support to descend by gravity toward said work bed, and bring said work tool or point into operative engagement with a printing surface upon said work bed, and a resistance device operative upon said support to control the descent thereof under gravity, whereby sufficiently forceful impact of said work tool or point with the printing surface, to mar same, is prevented. 100
15. A machine of the character described, embodying therein a work bed, a carriage mounted to have universal movement upon a single plane, a movable support for a work tool or point mounted upon said carriage, a work tool or point carried thereby, a transmitter arm, a universal joint connecting one end of said arm with said carriage, a support for said transmitter arm, a universal joint connecting said support with said transmitter arm intermediate the ends thereof, means whereby said support may be adjusted toward and from said carriage to vary the operative leverage of said arm, to vary the scale of reproduction, means whereby said support may be tilted to one side or the other, to tilt the reproduction, means whereby said support for the work tool or point may be adjusted radially of its pivots, a member operative upon said support to move it away from said work bed, means whereby said member may be moved away from said support to permit said support to descend by gravity toward said work bed, and bring said work tool or point into operative engagement with a printing surface upon said work bed, and a resistance device operative upon said support to control the descent thereof under gravity, whereby sufficiently forceful impact of said work tool or point with the printing surface, to mar same, is prevented. 105

In witness whereof I have hereunto affixed my signature, this 10th day of December, 1918, in the presence of two subscribing witnesses.

WILLIAM S. EATON.
